CABINET BED

Jacques L. Godschalk, Chicago, Ill.

Application March 22, 1949, Serial No. 1,552

Term of patent 7 years

(Cl. D5—4)

To all whom it may concern:

Be it known that I, Jacques L. Godschalk, a citizen of the United States, residing at Chicago, in the county of Cook and State of Illinois, have invented a new, original, and ornamental Design for a Cabinet Bed, of which the following is a specification, reference being had to the accompanying drawing wherein:

Fig. 1 is a view in perspective of a cabinet bed, swung to its down position, showing my new design; and

Fig. 2, which is a similar view, shows the bed folded up within the cabinet and out of sight.

I claim:

The ornamental design for a cabinet bed, as shown.

JACQUES L. GODSCHALK.
